UNITED STATES PATENT OFFICE.

HARRY M. COOPER, OF OAK PARK, ILLINOIS.

SELF-LOCKING SEAL.

1,160,853.

Specification of Letters Patent. Patented Nov. 16, 1915.

Application filed June 4, 1915. Serial No. 32,048.

To all whom it may concern:

Be it known that I, HARRY M. COOPER, a citizen of the United States, and resident of Oak Park, in the county of Cook and State 5 of Illinois, have invented certain new and useful Improvements in Self-Locking Seals, of which the following is a specification.

My invention relates to seals, and more particularly to such as may be employed as 10 tell-tale devices adapted to show whether the articles to which they are secured have been tampered with; and in that general class it relates more particularly to such as have interlocking elements for giving the 15 device its sealing character.

The general object of seals of this class is to show whether the car doors, vehicles, or any relatively movable or separable parts, or packages sealed thereby have been opened or 20 tampered with.

The principal object of the present improvements is to provide a device whereby this general object is effectively attained.

A particular object is to improve the construction and efficiency of devices of the character illustrated, whereby the seal may not be broken without at the same time so mutilating it as to render that fact obvious to the casual inspector and as to avoid the 30 reassembling of the parts so as to present the appearance of a seal untampered with.

Other objects and advantages will appear hereinafter.

In the accompanying drawings, which 35 form a part of this specification, I have illustrated a preferred embodiment of these improvements as applied to a seal of the character and general construction illustrated in the patent referred to.

40 In these drawings Figure 1 shows the device complete as when in use; Fig. 2 is a face view of the blank from which the seal is made; Fig. 3 is a fragmentary view of the housing end of the seal partially bent or folded and scored; Fig. 4 is a fragmentary perspective of the hook end of the seal; Fig. 5 is a broken medial longitudinal section of the device, on an enlarged scale; Fig. 6 is a fragmentary medial section showing the 45 hook end of the seal interlocked in the housing end; Fig. 7 is a transverse section through the device of Fig. 5, as on the line 50

7—7 thereof in the direction of the arrows; and Fig. 8 is a fragmentary perspective of the interlocked ends of the seal after breaking strains have been brought to bear upon it, the parts being only partially separated.

The blank 10 is ordinarily formed of thin and flexible material, suitably tin plate. The housing end has body portions 11 and 12 adapted to form side walls of the box or housing, these portions having respectively the wings or ears 11^a and 12^a respectively adapted to be folded interlockingly upon each other, as well shown in Fig. 7. Before 65 the side walls are thus locked together, however, the portion 13 is folded through an angle of 180° on the line a—b (Fig. 2), the partially detached portion 14 is turned up substantially at right angles, and the tongue-like piece 15 is inclined away from the portion 12, as shown in Fig. 5. The portion 11 is stamped outward, as at 16, to provide a seat or pocket for the fin or projection 14, both for the purpose of holding it against 70 lateral displacement as well as to prevent the tampering insertion of a thin blade over the top of the projection 14. The leaf or tongue-like portion 15 normally rests against the wall 11 under its own spring 75 pressure.

What I am designating as the hook end of the strip is provided with the longitudinal slot or opening 20, preferably widened somewhat as at 20^a, the end portion being turned 80 over to provide the hook 21 on the side of the strip 10 opposite to that of the opening 17 in the end of the box or housing. The hook end is preferably stamped with ribs, as 23, both for purposes of strength and to 85 thicken generally this hook end at these ridges whereby when the parts are in interlocked relation, as in Fig. 6, the opening 17 is substantially filled with this hook end of the device whereby it would be quite difficult, 90 if not impossible, to insert a blade effectively in the housing to unhook the connections. The projection 14 co-operates in this safety provision in forming an obstruction in the path of such blade and constituting a 95 guard for the interlocked elements 15 and 21.

From the description thus far it will be clear that when the hook end of the seal is passed into the opening 17 of the box or

housing, with the slot 20 accommodating the projection 14, the hook 21 will become interlocked with the tongue or engaging device 15, securing the parts together. Experience 5 has shown that if strains of such force as to break the device are now brought to bear upon it the hook 21 either breaks off entirely or is turned back into a straightened-out position, whereupon this hook end as a whole 10 may be withdrawn from the housing, and after the car has been rifled of its contents, or other nefarious acts performed, according to the nature of the article sealed, the wrongdoer may simply replace the car door 15 or other parts as they were, position the seal as before, and insert the hook end in the opening 17 of the housing as before, no substantial if any actual change being made in the appearance of the seal, and thus detection 20 of the offense by the usual inspection is avoided.

To render this kind of device highly efficient and unobjectionable from the standpoint mentioned I form or modify a portion 25 of the seal whereby it is so relatively weak that breakage must inevitably occur at that place, and must give rise to such breakage as renders the device incapable of further assembling as a seal or with the appearance 30 of a seal unbroken. To this end I preferably cut or score the wall 11, immediately contiguous to the strip part denominated 10, and on a line or lines, as at 24, extending from the open end of the housing and connected 35 together by similar scoring or cutting, as at 25, thus weakening the connection between the strip portion 10 and the housing whereby when breakage occurs a portion of the wall 11, as 11^b, is actually broken or torn 40 away from the rest of the device, as partly illustrated in Fig. 8. When so broken the outer and visible portions of the seal are so mutilated that the most casual inspection will readily reveal any attempt to conceal 45 the breakage. The scoring or cutting, as at 24, 25, may be done by means of a sharp stamping tool, severing the metal partially but leaving it strong enough to withstand rather severe strains. The directions and 50 extent of such cutting or weakening may be varied. The place where so cut, however, is weaker than the hook 21 and gives way before the hook breaks. In practice a strong pull or yank with a bale hook or rod held by 55 the two hands is necessary to break the device.

I have thus provided a strong seal, of simple construction, and one of very notable effectiveness in overcoming the serious disadvantages hereinabove pointed out.

In my practice a single punch-and-die machine cuts and forms the seal by a series of operations. Anyone skilled in the art of such light metal stampings will readily be

able to manufacture the device according to 65 methods now well understood.

While I have illustrated and described a preferred embodiment of these improvements, the same are susceptible of modification without departure from the spirit of 70 the disclosure herein made, and all such changes and modifications are contemplated by me as fall within the scope of the appended claims.

I claim:

1. A locking seal comprising a piece of 75 flexible material adapted to be bent loop-shaped and having a box-like housing at one end thereof, said housing having an opening to receive the other end portion of 80 the device, interlocking means within said housing and at the other end portion of the device respectively whereby when said other end portion is normally inserted through said opening and into said housing said 85 means within the housing and at said other end portion coact to lock the two ends of the device together, a wall of said housing directly connected to said flexible piece being 90 relatively weak on a line extending from 95 said housing opening on one side of said flexible piece to the housing opening at the other side thereof whereby strains insufficient to break said interlocking means will break away a portion of said housing. 95

2. A locking seal comprising a piece of 100 flexible material adapted to be bent loop-shaped and having a box-like housing at one end thereof, a wall of said housing merging directly and contiguously into said flexible 105 piece, said housing having an opening to receive the other end portion of the device, interlocking means within said housing and at the other end portion of the device respectively whereby when said other end portion is normally inserted through said opening and into said housing said means within 110 the housing and at said other end portion coact to lock the two ends of the device together, a portion of said housing directly connected to said piece of material being relatively weak whereby strains insufficient to break said interlocking means will break away a portion of said housing. 110

3. A locking seal comprising a strip of 115 thin and flexible material having integrally formed body portions at one end, one of said body portions being adapted to be folded over the other thereof, said body portions respectively having wings adapted to be 120 folded upon each other whereby a housing is formed open at one end, one of said body portions merging directly and contiguously into said strip proper at said open end, said body portion so directly connected to said strip proper being weakened on a line extending from said strip proper into said 125 body portion, interlocking means within

said housing, and co-operating interlocking means at the other end of said strip proper, said locking means being such that when said other end of the strip proper is normally inserted through the opening of said housing the two ends of the device are locked together, said weakened portion of said housing being adapted to break away when

strains insufficient to break said locking means are brought to bear upon the device 10 when in use.
